LAMP

Fred P. Greve, Berrien Springs, Mich. 49103

Filed June 15, 1967, Ser. No. 7,482

Term of patent 14 years

(Cl. D48—20)

FIG. 1

FIG. 4

FIG. 2

The lamp is essentially round and appears the same from any angular position. The side elevational view of FIGURE 1 is representative of the remaining sides.

The dominant features of my design reside in the portions shown in full lines.

I claim:

The ornamental design for a lamp, substantially as shown and described.
